Inventor I
J. Matthews

UNITED STATES PATENT OFFICE.

JAMES MATTHEWS, OF MIDDLETOWN, PENNSYLVANIA, ASSIGNOR TO HIMSELF AND HENRY EGOLF, OF SAME PLACE.

GRAIN-SEPARATOR.

Specification of Letters Patent No. 31,577, dated February 26, 1861.

To all whom it may concern:

Be it known that I, J. MATTHEWS, of Middletown, in the county of Dauphin and State of Pennsylvania, have invented a new and 5 Improved Grain-Separator; and I do hereby declare that the following is a full, clear, and exact description of the construction and operation of the same, reference being had to the annexed drawings, making a part 10 of this specification, in which—

Figure 1, is a perspective view, of the back end of the separator, and Fig. 2, is a perspective view of part of the front end of it. Fig. 3, is an enlarged view of the ball plate, 15 and ball, and Fig. 4 is an enlarged view of the cup and its plate. Figs. 5 and 6, are perspective views of the plates shown in Figs. 3 and 4.

The nature of my invention consists in 20 placing a vertical screen, in the front end of the shoe, in front of the horizontal screens, and a plate, ball, and inverted cup, to hold up the front end of the shoe.

To enable others skilled in the art, to 25 make and use my invention; I will proceed to describe its construction, and operation.

I construct my grain separator in the usual form.

A, A, is the frame, which is made as 30 usual.

B, is the vertical screen. It is fastened in a permanent manner in the front end of the shoe, right under the grass seed box. It is intended to hold the grain which is not completely separated from the chaff, or lightcaps, from falling front of the horizontal screens, so that it may be separated from the chaff, or lightcaps, by being rubbed, and shaken, on the horizontal screen, until it is 35 loosened from the lightcaps, so that the grains pass through the screen, and are saved and the lightcaps are blown back with the chaff. The said vertical screen should be so fine as to prevent any grains from passing 40 through it; each mesh should be about one eighth of an inch in size. By using said vertical screen, I am enabled to separate damp grain, in a perfect manner, as I need not blow so hard as to blow it back with the 45 chaff, but hard enough to dry it, and separate it perfectly from the lightcaps, and chaff. The air from the fan, passes through 50

said vertical screen, with but little obstruction, and thus passes under, and over, the horizontal screens, in a manner not obtainable without the use of said vertical screen. The advantages of my vertical screen, are 55 very great, as by using it in my grain separators, I am enabled to save all the grains covered by lightcaps, in a very simple, and 60 easy manner, and it is durable, and not liable to be injured, or put out of order.

C, Fig. 2, is a small plate of iron, permanently fastened near the top of the frame, just under the cap of the frame, and above, 65 and in front of the shoe, and screens. On said plate, is a small ball, which ball, is kept in place by the inverted cup E. The cup E, is permanently fastened to the front part of the shoe, and it rests, and moves, on the 70 small ball, or balls, under it with less friction than any other mode of arrangement. I use the cup in the inverted form, so as to have the plate below, so that the dirt will not collect in the cup. One ball is sufficient, 75 but two, or more balls may be used, with good effect. On the front of cup E, is a small projection with a hole in it, in which the end of rod D, is hooked. The motion of rod D, is given as usual, by the fan shaft, 80 and a small crank &c.

Fig. 3 is an enlarged view of the ball plate and ball. C represents the plate and K the ball. This plate is fastened as described on page 3rd.

Fig 4 is an enlarged view of the cup and its plate. E represents the plate and H the cup, which is inverted upon plate C and over the ball K, so as to keep the ball K to its place. I invert the cup to prevent the dirt 85 from collecting in the cup H. The cup plate E is fastened as described on page 3rd of my specification. J represents the screws by which plates E and C are fastened. I represents the hole on the front end of plate 90 E in which the end of rod D is hooked as described on page 3rd of my specification.

The same letters on different figures represent the same thing. The said plate, cup and ball, or balls, make the most durable, 100 and free arrangement for operating the front end of the shoe, and it is so simple as to cost but a triffe, and it gives the shoe a very rapid motion, or shake, which is nec-

essary to separate the grain, from the light-
caps and chaff. The back end of the shoe
hangs on two hooks, as usual.

I claim—

- 5 1. The employment of the vertical screen
D, arranged in relation to the fan and the
horizontal screens of the shoe between said
shoe and fan as and for the purpose speci-
fied.

2. The employment of the plate E, as con- 10
structed the plate C, and the ball K, in con-
nection with the shoe whereby said shoe is
hung and allowed to vibrate at its front
end substantially as specified.

J. MATTHEWS.
